(57) **CLAIM**

The ornamental design for a lever handle for fittings, as shown and described.

DESCRIPTION

FIG. 1 shows a front view of the design according to an embodiment of the invention.

FIG. 2 shows a top plan view of the design according to an embodiment of the invention.

FIG. 3 shows a rear view of the design according to an embodiment of the invention.

FIG. 4 shows a right side view of the design according to an embodiment of the invention.

FIG. 5 shows a left side view of the design according to an embodiment of the invention; and,

FIG. 6 shows a sectional view of the design according to an embodiment of the invention taken along the line 6—6 as shown in FIG. 2.

The bottom plan view is a mirror image of the top plan view as shown in FIG. 2.
